UNITED STATES PATENT OFFICE.

SUMNER R. BIXBY, OF WORCESTER, AND JOSEPH B. BANCROFT, OF MILFORD, MASSACHUSETTS.

IMPROVEMENT IN SHUTTLE GUIDES OR GUARDS FOR LOOMS.

Specification forming part of Letters Patent No. 43,828, dated August 16, 1864.

To all whom it may concern:

Be it known that we, SUMNER R. BIXBY, of Worcester, and JOSEPH B. BANCROFT, of Milford, in the county of Worcester and State of Massachusetts, have made a new and useful invention, having reference to Shuttle Guides or Guards for Looms for Weaving; and we do hereby declare the same to be fully described in the following specification and represented in the accompanying drawings, of which—

Figure 1 denotes a top view, and Fig. 2 a front elevation of a reed-cap and shuttle guide or guard and its supports as provided with our invention. Fig. 3 is an end view of the same. Fig. 4 is a longitudinal section of the said guide or guard and its supports. Fig. 5 is a side view, and Fig. 6 a horizontal section, of one of the supports. Fig. 7 is a side view of the guard or guide.

The object of our invention is to enable the guide or guard, when turned into its lowest position over the race-beam of the lay of a loom, to be securely fastened in place, so as not to be liable to vibrate independently of the lay or to be thrown out of place by the shuttle.

The purpose of the guide or guard is well known to weavers or loom-makers, the said guide or guard being an appliance of the loom and used to prevent the shuttle, while in motion across the race-beam, from being turned from its true course by knots or threads of the warps or other means, which, were it not for the guard, would cause the shuttle to be thrown either entirely out of the loom or into the warps so as to endamage them or do injury to the loom or to an object in the vicinity thereof.

In the drawings, A denotes the reed-cap or that bar which usually covers or caps the reed and is supported by the lay of a loom. B is the shuttle guide or guard, which in this instance consists of a rod of metal bent in the form represented in the drawings, and particularly in Fig. 7, in which it is shown as hav-

ing two journals, a and b, extending in one and the same direction from the rest of the guard, and with the longer of them furnished with a male screw, c, cut on it, and having a corresponding screw-nut, d, screwed on the said screw. Each of the two journals a b extends horizontally through one of two supports, C C, which project from the reed-cap A, and are confined thereto by means of screws or other proper devices. Each of the supports C is constructed with or has a recess or socket, e, extending vertically within it and below the journal of the guard, the said socket e being to receive the next adjacent arm, f, of the guard and to fit closely thereto, so as to prevent the guard from being revolved in its bearings, while such guard may be in the socket and the clamp-nut d may be screwed up against the support c. On unscrewing the clamp-nut sufficiently, the guard may be moved endwise, so as to move its arms out of the sockets of the supports, which having been accomplished, the guard will be free to be moved upward into the position as represented by the dotted lines in Figs. 2 and 3.

It is not necessary to our invention that each of the guard-supports should be provided with a socket, as described, as it would suffice to have but one of them so provided, but when there is a socket to each of such supports, the guide or guard will be better supported by them, as each of them when containing the guard would serve to prevent it from being revolved.

We do not claim the combination of a bar or shuttle-guard with a cloth-weaving loom or the lay thereof in such manner as to serve as a means of preventing the shuttle from being thrown out of its true course while in flight from one shuttle-box toward the other; nor do we claim the application of such a guard to the lay or reed in such manner as to be capable of being turned upward or from one position to another and fastened in either, as all this has been accomplished before our

invention and will be found described in the United States Patents numbered 9,263 and 12,593.

We claim—

The combination of the clamp screw and nut and the arm socket or sockets, or the equivalents thereof, with the guard-supports and the guard, constructed and applied together, substantially as described—viz., so that the guard may be capable not only of being turned laterally, but of being moved

longitudinally within the said supports, and either into or out of the socket or sockets, in manner and for the purpose as specified.

SUMNER R. BIXBY.

JOSEPH B. BANCROFT.
